UNITED STATES PATENT OFFICE.

JAMES A. CHARTER, OF CHICAGO, ILLINOIS.

GAS ENGINE.

Application filed March 31, 1921. Serial No. 457,207.

This invention relates to gas engines of the general type illustrated in my prior Patent No. 1,106,782, dated August 11, 1914, in which a rotatable sleeve valve is mounted between inner and outer cylinders, the inner cylinder being capable of longitudinal expansion into the crank case which carries the cylinder mechanism.

The object of this invention is to provide a novel manner of mounting and centering the inner cylinder with reference to the outer cylinder and so applying the cylinder head thereto as to securely hold the inner cylinder at its upper end in centered position and against endwise motion.

The invention consists in means for carrying out the foregoing objects which enable the use of different materials for the inner cylinder and for the cylinder head, thereby reducing not only the expense of the materials themselves, but the amount of machine and foundry work required; by making the inner cylinder in two parts make it possible to discard one of them either when worn out in actual use or injured in construction work without it being necessary to replace both parts. The invention further consists in features and details of construction hereafter more fully set forth in the specification and claims.

The single figure of the drawing shows a conventional form of outer cylinder 2, water jacketed at 4, carrying on its lower end crank case 6 within which is mounted the crank shaft mechanism 8 including the connecting rod 10 and attached piston 12. Rotatably mounted is the, for the purposes of this case, conventional rotatable sleeve valve 14, driven by gear mechanism 16 propelled by the worm 18 driven from the crank shaft by the gearing 20. Inside of this rotatable sleeve, is freely slipped from the top, a non-threaded inner cylinder 22 which is at its lower end conventional as to this case in that it slides vertically with reference to centering blocks 24 and 24^a provided for the purpose located at the upper end of the crank case. Especial attention is called to the fact that the two blocks 24 form the lower end of the cylinder 2-4; that the upper block, preferably made of hard steel, forms the bottom or thrust seat for the gear 16 carrying the sleeve valve 14, the oil which necessarily encloses said gear being sealed in by said ring 24; also that the inner cylinder 22 slides through both said rings and that its lower

end extends to—but not below—the lower ring 24 by which it is guided and centered in relation to the bore of the cylinder 2-4 provided with water jacket 4. This construction in combination with the means for sustaining the upper end of cylinder 22, elsewhere described, insures accurate centering of all parts of the inner cylinder while permitting its necessary longitudinal expansion, thus insuring a space or cavity between the inner and outer cylinders extending the entire length of the valve of proper size at all times to insure proper rotation of the valve 14. If the inner cylinder is not so centered the side thrust of the piston due to angular position of the connecting rod will, in certain positions, force the inner cylinder against the sleeve valve and partially or wholly lock it.

The upper end of this inner cylinder 22 is in accordance with the improvement of this invention provided with an angularly outwardly extending flange 26 of greater diameter than the bore of the outer cylinder 80 against which sleeve valve 14 rotates so that it rests in an annularly cut recess 28 preferably of cylindrical circumference whereby the weight of the inner cylinder 22 is carried on a ledge or shelf 30 formed in the end of 85 the outer cylinder while the inner cylinder is centered against lateral movement by the outer circumferential wall of the cut 28. For the purposes of this centering it is of great importance that the outer circumference of 90 flange 26 be concentric with the outer circumference of the inner cylinder.

The upper end of the inner cylinder is closed by a non-threaded cylinder head 32 extending any desired predetermined distance into the cylinder and having integral laterally extending flange or lug 34 fitting over and embracing the upper horizontal flange on the inner cylinder and holding it tightly in place within the notch 28 provided for it and on the shelf 30 provided for it, said flange or lug being provided with a suitable retaining device, that shown in the drawing being the conventional lag bolts 36.

The cylinder head is provided with a conventional form of water jacket 38.

By the use of this construction the inner cylinder 22 can be made of one material preferably a hard material, while the cylinder head 32 can be made of an entirely different material, usually a softer and more workable

one, or it can be made of aluminum for lightness, a material which would not be feasible for the inner cylinder 22.

With the inner cylinder made separate 5 from the cylinder head it is much cheaper and easier to accurately machine its upper flange 26 to fit into the recess 28 provided for it, to thereby accurately center the inner cylinder with reference to the outer cylinder, 10 than is possible where the inner cylinder is made integral with the cylinder head and the securing flange, as in prior constructions.

The lower end of outer cylinder 2 terminates in inturned flange 78 against which 15 rings 24 and 24^a bear and seal thus forming oil space 80 filled with oil in which gear 18 rotates.

Having thus described my invention, what I claim as new and desire to secure by Letters 20 Patent, is:—

1. In mechanism of the class described, an outer cylinder having at each end an annular notch of greater diameter than the bore of the cylinder, and concentric therewith, a 25 smooth bore unthreaded inner cylinder sufficiently smaller than the outer cylinder to take a sleeve valve between them, a flange on one end of the inner cylinder centered in said notch in one end of the outer cylinder, an 30 unthreaded water jacketed plug shaped head 32 entering and bearing against the inner wall of the inner cylinder securing said flange in said position, the length of said unthreaded plug being substantially equal to the diameter 35 of the bore of the inner cylinder to thereby present an effective seal, means securing said head in place, a positioning ring inserted in the annular notch at the other end of the outer cylinder enclosing and centering the opposite 40 end of said inner cylinder, a second ring in said notch rigidly secured to the cylinder wall retaining the first ring in position, there being formed adjacent said first ring an annular oil space closed by said ring, said oil space 45 being of greater diameter than the bore of the outer cylinder, a sleeve valve rotatable between the inner and outer cylinders, rotat- 50 ing in unison with a gear entering and running in said oil space within the outer cylinder, and positioned lengthwise by the first ring and by the flange on the inner cylinder.
2. A gas engine comprising an outer cylinder having, at each end an annular notch of greater diameter than the bore of the cylinder, a 55 smooth bore unthreaded inner cylinder arranged within the outer cylinder, a sleeve

valve arranged between the inner and outer cylinder, a flange carried at one end of the inner cylinder and centered in a notch at one end of the outer cylinder, an unthreaded 60 water jacketed plug securing said flange in said position, a positioning ring inserted in the annular notch at the opposite end of the outer cylinder for enclosing and centering the opposite end of said inner cylinder, a 65 second ring in said notch rigidly secured to the cylinder wall and retaining the first ring in position, there being formed adjacent said first ring, an annular oil space closed by said ring, said oil space having greater diameter 70 than the bore of the outer cylinder, said sleeve valve being rotatable between the inner and outer cylinders, and a gear entering and running in said oil space within the outer cylinder, and rotating in unison with the 75 sleeve valve, said sleeve being positioned lengthwise by the first ring and by the flange on the inner cylinder.

3. A gas engine comprising an outer cylinder having, at each end, an annular notch of greater diameter than the bore of the cylinder and arranged concentrically with the cylinder, a smooth bore unthreaded inner cylinder sufficiently smaller than the outer cylinder to receive a sleeve valve between the cylinders, 80 a flange formed in one end of said inner cylinder and centered in a said notch at one end of the outer cylinder, an unthreaded water jacketed plug shaped head entering and engaging the inner wall of the inner cylinder 85 for securing said flange in said position, means for securing said head in place, a positioning ring arranged in the annular notch at the opposite end of the outer cylinder, said positioning ring embracing and centering the opposite end of said inner cylinder, a second ring arranged in said notch and fastened to the cylinder wall to retain the first ring in place, an annular oil space formed 90 and arranged in said outer cylinder adjacent said first ring, a sleeve valve rotatably mounted between the inner and outer cylinders, and a gear entering and running in said oil space and having driving engagement with said sleeve valve for rotating the same, said sleeve valve being positioned longitudinally by the first ring and by the flange on said inner cylinder.

In witness whereof, I have hereunto subscribed my name.

JAMES A. CHARTER.
